(57) **CLAIM**

The ornamental design for a fly swatter cover, as shown and described.

DESCRIPTION

FIG. 1 is a front elevation view of the fly swatter cover showing my new design in the down position;

FIG. 2 is a left side view of the invention in the up position;

FIG. 3 is a front elevation view of the invention in the up position;

FIG. 4 is the right side view of the invention in the down position;

FIG. 5 is a perspective view of the invention;

FIG. 6 is a top plan view of the invention; and,

FIG. 7 is bottom plan view of the invention.

The broken line showing of environment in the drawings is for illustrative purposes only and forms no part of the claimed design.
